GAS-DETECTING ATTACHMENT FOR MINERS' SAFETY-LAMPS.

SPECIFICATION forming part of Letters Patent No. 722,555, dated March 10, 1903.

Application filed April 10, 1902. Serial No. 102,316. (No model.)

To all whom it may concern:

Be it known that we, JAMES T. BEARD and MATTHEW D. MACKIE, citizens of the United States, residing at Scranton, in the county of Lackawanna and State of Pennsylvania, have invented certain new and useful Improvements in Gas-Detecting Attachments for Miners' Safety-Lamps, of which the following is a specification, reference being had

thereto in the accompanying drawings.

Our invention relates to gas indicators and detectors used in connection with miners' safety-lamps; and the objects of the invention are to provide a simplified and inexpensive construction for such indicators, to render such indicators attachable to the ordinary safety-lamps now in use, to render them more easily attachable and detachable, to detect with greater certainty the percentages or quantities of gas present, and other objects, as herein specified and claimed. To accomplish these purposes, our present invention is comprised in the construction, arrangement, and combination of the parts, as specified, and illustrated in the drawings, in which—

Figure 1 is a side elevation of a miner's safety-lamp with parts of the gauze and bowl broken away to more clearly show the attachment of one of our detecting attachments. Fig. 2 is a detail view showing the construction of the base-piece of one of our detectors in the form illustrated in Fig. 1. Fig. 3 illustrates a substitute form of constructing the base-piece in which the said base is fitted around the wick-tube. Fig. 4 is an additional substitute form where the base-piece is substituted by a continuation of the wires forming the sides of our device and more especially adapting it to be fitted against the walls of the gauze of the lamps. Fig. 5 shows an additional substitute form for the base-piece constructed of sufficient width to be clamped between the upper and lower parts of the lamps when the bowl is screwed thereon. Fig. 6 is an additional substitute form adapted to be sprung or clasped around the bushing which usually surrounds the wick-tube in such lamps.

50 Other methods might be resorted to as means for attaching our detectors to lamps

now in use; but the foregoing will be sufficient to illustrate the general character of our claims with reference to means of attachment to the lamp.

55

In the drawings, 1 denotes a supporting-frame constructed from a continuous wire or metallic strip bent in the general form of an inverted U and secured to the body of a miner's safety-lamp 2 in such relation that the wick-tube 3 occupies a middle position with reference to the two sides of the frame 1. Stretching across to the opposite sides of said metallic frame and directly over the wick-tube aforesaid are strands 4 5 6, &c., which are preferably made from platinum wire, but may be constructed from any other suitable incandescent substance. Any desired number of these strands may be attached and at such distances as may be deemed advisable and at 60 such points as may be determined upon to represent the several percentages or fractions of percentages of gas present, the principle on which the device operates being that the heat of the flame will cause a strand or bit 65 of wire or other incandescent substance to be heated to a red color at a height above the flame in direct ratio to the amount of gas present. In practice we prefer, if possible, to have the supporting-frame 1 secured directly to the milled ring 7, which is common in most lamps, to secure the wick-tube 3 into position by clamping the flange 8 thereof between the threaded rim 9 of the ring 7 and the diaphragm 10 of the lamp-bowl. When 70 the substitute form shown in Fig. 3 is used, the base-ring 7 is substituted by a disk 11, which is notched at 12 for the purpose of accommodating the wick-adjuster 13 and has a central opening to accommodate the wick-tube when this form is used. The disk 11 is clamped by an ordinary milled ring 7 aforesaid, the said base 11 coinciding with the flange 8 of the wick-tube. When the base-piece is eliminated, as shown in Fig. 4, one 75 or more coils 14 may be constructed and arranged to impinge against the sides of the ring 15 of the upper part of the lamp, and when the substitute form shown in Fig. 5 is used a base-plate 16, with an opening 17 80 large enough to accommodate the bushing 18, is secured to the lower end of the supporting-

100

frame 1 by any suitable means. The edges of said flange may or may not be clamped between the diaphragm 10 of the bowl and the lower rim 15 of the upper part of the lamp in securing them together. When the form shown in Fig. 6 is used, a rigid piece 19, crescent in form, is soldered or otherwise secured to the lower end of the supporting-frame 1 and is provided with clips or springs 20, which 10 may be sprung apart with the fingers, so as to permit the device to be slipped over the neck or bushing 18 of the bowl of the lamp.

The operation of the device is apparent. The supporting-frame, with its sensitive strands 4 5 6, &c., is arranged within the lamp to be used, and the said strands are shifted to positions, determined by experiment, in which they represent percentages of gas present by becoming reddened with 20 the heat of the flame, it being apparent, of course, that where high percentages of gas are present and one of the upper strands is reddened the intermediate and lower strands will also be heated to a redness. The user of 25 the lamp of course will be informed of the danger limit and when the strands are heated to an unusual or dangerous height will abstain from working in such gaseous quarters.

We have thus produced an inexpensive device which may be arranged to indicate any 30 of the usual percentages of gas and may be attached to the common forms of lamps.

We do not wish to be confined to the means of attachment shown, as many attachments 35 may be resorted to which will support a series of sensitive substances over the flame of a

miner's lamp without departing from the spirit of our invention.

Therefore what we claim, and desire to secure by Letters Patent, is—

1. In a miner's safety-lamp, a supporting-frame, a series of wire strands supported, by said frame, over the flame of the lamp, the said wire strands being arranged at varying heights above the said flame, in combination 45 with means for securing the said frame to the wick-tube of the lamp, substantially as and for the purpose specified.

2. A gas-detecting attachment for miners' safety-lamps comprised in a Ω -shaped supporting member, a series of wires arranged on said supporting member, a base-piece connecting the ends of said member, and means for attaching the said base-piece to the lamp so as to hold the said supporting member vertical and over the wick-tube of the lamp, substantially as and for the purpose specified.

3. In a gas-detecting attachment for miners' safety-lamps, a supporting-frame adapted to support a series of wires or other suitable 60 bodies over the flame of the lamp, the said frame being provided with means for attaching the same to the lamp, for the purpose as specified.

In testimony whereof we affix our signatures in presence of two witnesses.

JAMES T. BEARD.
MATTHEW D. MACKIE.
